UNITED STATES PATENT OFFICE

JOHN R. DENNIS, OF PROVIDENCE, RHODE ISLAND, ASSIGNOR TO INTERNATIONAL BRAID COMPANY, OF PROVIDENCE, RHODE ISLAND, A CORPORATION OF MASSACHUSETTS

LACING TIP

Application filed October 21, 1924. Serial No. 744,937.

The object of this invention is to provide a lacing for shoes, corsets and other articles with a tip of celluloid or other suitable material, having its surface figured to simulate 5 the surface of the fabric to which it is attached.

With these and other objects in view, the invention consists of certain novel features of construction, as will be more fully described, 10 and particularly pointed out in the appended claim.

In the accompanying drawings:—

Figure 1 is a perspective view illustrating 15 a tip of celluloid or the like formed on the end of a fabric lacing, and showing the surface of the tip as being figured to simulate that of the fabric to which it is attached.

Figure 2 is a perspective view illustrating 20 a pair of dies which are adapted to apply a strip of celluloid to a lacing to form a tip thereon and the working surface of the dies as being figured to impress the same upon the surface of the tip causing it to simulate the fabric to which it is attached.

Figure 3 is a perspective view of a strip 25 of celluloid which has a plain surface before it is applied, to form a tip upon the lacing.

It is found in the practical use of shoe lacings, corset lacings and the like, of advantage 30 to apply a strip of celluloid about the lacing to compress the lacing and hold it in compressed position and to soften the inner surface of the strip by means of a solvent or by heated dies or both, to cause the inner surface

35 thereof to intimately unite with the surface of the fabric; also to figure the working surface of these heated dies so that when acting upon celluloid to compress it about the lacing the heat of the dies will serve to soften 40 and impress the outer surface of the tip causing it to simulate or take on the appearance of the fabric to which it is attached and as the tipping material is of the same color as

45 that of the lacing it is difficult to tell the difference between the lacing material and the tip, which adds to the attractive appearance, the salability, and therefore, the value of the lacings having tips so figured; and the following is a detailed description of the present 50 embodiment of my invention showing one

means by which these advantageous results may be accomplished:—

With reference to the drawings, 10 designates a lacing which is preferably formed of braided fabric but which may be made of any suitable material. On this lacing is shown a tip 11 which is formed of a strip 12 of celluloid or other suitable material adapted to be softened by application of a solvent or by heat or by both solvent and heat. This material is 55 preferably cut in strip form, as illustrated in Figure 3, and through action of dies 13 and 14, folded or rolled about the lacing to compress the lacing at that point and hold it securely in compressed position, the inner 60 surface of the celluloid being treated with a solvent causing it to soften and when compressed onto the lacing to intimately unite 65 with the surface of the fabric and remain in set position; also the surface of the strip may be softened by heating the dies 13 and the working surface 15 of these dies may be figured so as to impress the softened, outer surface 70 of the celluloid with these figures causing this outer surface of the celluloid to simulate or represent the surface of the fabric of the lacing to which it is attached, the color 75 of the strip being similar to that of the lacing to which it is applied causing the tip to so closely simulate the fabric as to be difficult to tell where one begins and the other leaves off. 80

My improved form of tip having its surface like that of the fabric to which it is attached enhances the appearance of the tip and renders the same more valuable. 85

The foregoing description is directed solely towards the construction illustrated, but I desire it to be understood that I reserve the privilege of resorting to all the mechanical changes to which the device is susceptible, the invention being defined and limited only by the terms of the appended claim. 90

I claim:

A celluloid tip for a fabric lacing, said tip having spaced indentations and raised portions forming a pattern which simulates the appearance of the fabric. 95

In testimony whereof I affix my signature.

JOHN R. DENNIS. 100
